CONSOLE FOR COST ESTIMATION DATA PROCESSOR

Richard Anderson, Los Altos, Calif., assignor to
Varian Associates, Palo Alto, Calif.

Filed Oct. 10, 1974, Ser. No. 513,679

Term of patent 14 years

Int. Cl. D14—02

U.S. Cl. D26—5 C

FIG. 1

FIG. 2

FIG. 3

FIG. 4

FIG. 5

FIG. 1 is a front perspective view of a console for cost estimation data processor showing my new design.

FIG. 2 is a rear elevational view thereof.

FIG. 3 is a top plan view thereof.

FIG. 4 is a front elevational view thereof.

FIG. 5 is a side elevational view thereof.
The side of the device which is not shown in FIG. 5 is substantially identical to the side which is shown.

I claim:

The ornamental design for a console for cost estimation data processor, as shown and described.
